UNITED STATES PATENT OFFICE

90,863

DESIGN FOR A COMPOSITE UNIT MOUNTING FOR JEWELRY

Karl R. Staufenbeil, Indianapolis, Ind., assignor
to L. S. Ayres & Company, Indianapolis, Ind.,
a corporation

Application May 8, 1933. Serial No. 48,044

Term of patent 7 years

To all whom it may concern:

Be it known that I, KARL R. STAUFENBEIL, a citizen of the United States, residing at Indianapolis, in the county of Marion and State of Indiana, have invented a new, original, and ornamental Design for Composite Unit Mounting for Jewelry, of which the following is a specification, reference being had to the accompanying drawing, forming part thereof. In the drawing:

Fig. 1 is a top plan view of a composite unit mounting for jewelry, showing my new design; and

Fig. 2 is a side elevation of the same.

The dominant features of my design for a composite unit mounting for jewelry, consisting of a base of quadrilateral outline having mounted therein or thereon a large center stone, the cen-

tral plane of which is positioned at an elevation above the central plane or a common surface including the central planes of the border stones also mounted in or upon the base, the prongs or the like constituting the anchorage for the center stone, comprising radially directed division members between adjacent border stones, whereby the ornamental appearance of the center stone is enhanced and conveys the visual impression, since the border stones are substantially tangential to the center stone, that the center stone is of greater size than it actually is.

I claim:

The ornamental design for a composite unit mounting for jewelry, substantially as shown and described.

KARL R. STAUFENBEIL.
